UNITED STATES PATENT OFFICE

140,737

DESIGN FOR A PENDANT OR SIMILAR ARTICLE

Urie F. Mandle, New York, N. Y.

Application January 17, 1945, Serial No. 117,462

Term of patent 3½ years

(Cl. D45—15)

To all whom it may concern:

Be it known that I, Urie F. Mandle, a citizen of the United States of America, residing in New York, county of New York, and State of New York, have invented a new, original, and ornamental Design for a Pendant or Similar Article, of which the following is a specification, reference being had to the accompanying drawing, forming part thereof.

Fig. 1 is a plan view of a pendant or similar article showing my new design.

Fig. 2 is an edge view thereof.

The opposite side of the pendant as shown in Fig. 1 is plain.

I claim:

The ornamental design for a pendant or similar article, substantially as shown and described.

URIE F. MANDLE.
